ICE-MAKING TRAY

Lewis R. Smith, Norwalk, Conn., assignor, by
mesne assignments, to Phillippe L. Goetz,
Darien, Conn.

Application August 25, 1945, Serial No. 612,575

3 Claims. (Cl. 62—108.5)

1

This invention relates to ice cube making and dispensing devices.

In my copending application, Serial No. 605,570, now Patent No. 2,443,203 dated June 15, 1948, I have described a device for making and dispensing ice cubes in which an ice cube tray is disposed in a pivoted trough. When it is desired to release and dispense the ice cubes from the tray, warm refrigerant gases are caused to pass through the refrigerant coil which is in contact with the ice cube tray, and simultaneously the trough is filled with water. The warm gases and the water cause the ice cubes to loosen from the tray and the ice cubes float to the surface of the water. When the trough is filled with water, it becomes unbalanced and tilts on its pivotal axis thus dumping out the ice cubes and water.

The present invention relates generally to such an arrangement but particularly is concerned with a special form of ice tray, the ice compartments of which are so shaped that the ice "cubes" or blocks may be easily released therefrom, the ice blocks as they float upwardly from their compartments turning on their sides. Thus after being released from their compartments in the tray, the ice "cubes" cannot reenter their compartments when the water is dumped as the trough tilts. It is a principal object of the invention to provide an ice tray, the ice compartments of which are so formed.

These and other objects of the invention will become more apparent from the following description and claims when read in conjunction with the accompanying drawings in which:

Fig. 1 is a perspective view of an ice tray constructed in accordance with the invention.

Fig. 2 is a section through the tray taken on the line 2—2 of Fig. 3.

Fig. 3 is a sectional view taken on the line 3—3 of Fig. 2.

Fig. 4 is a perspective view of an ice "cube" such as formed in the tray.

Fig. 5 is a diagrammatic view showing the disposition of the tray in the trough, and

Figs. 6 and 7 are similar views showing respectively the position of an ice "cube", just being released from the tray, and the position it assumes upon reaching the surface of the water in the trough.

With reference now to Figs. 1, 2 and 3, an ice "cube" tray in accordance with the invention may be comprised of several pieces of sheet metal or the like. One such piece may be in strip form with one flat portion 10 constituting the vertical

2

back of the tray, and another portion 11 (bent at substantially a right angle to the back) forming the bottom of the tray. The bottom portion 11 at its forward end is curved upwardly in a forward flange 12 for a short distance.

The individual ice "cube" compartments are formed of a plurality of sheet metal strips each of which is bent into substantial U-form so as to comprise end walls 13 and 14 and a front wall 15. These compartment-forming U-bent strips are disposed with relation to first strip 10 so that the open end of the U faces the flat portion 10 forming the back of the tray.

The bottom edges of the end walls 13 and 14 abut the portion 11 forming the bottom of the tray, which bottom portion 11 thus forms the bottom of each ice compartment. The upwardly turned flange 12 of the bottom portion 11 overlaps the lower portion of the front wall 15 of each compartment strip. It will be noted that with this construction, a tray having any number of compartments may be easily constructed.

It should be particularly noted that the front wall 15 of each compartment is not parallel with the portion 10 which forms the vertical back wall of the tray. Instead each front wall is inclined at an angle thereto, flaring outwardly from bottom to top as clearly shown in Fig. 2. Moreover, the end walls 13 and 14 are non-parallel to each other flaring outwardly from the vertical from bottom to top as will be manifest from Fig. 3.

The strips forming the end walls 13 and 14 and the front walls 15 of the compartments of the tray are secured to the strip comprising the back portion 10 and the bottom portion 11, by any suitable means such as by welding, brazing, soldering, or the like. The manner of securing depends to a great extent on the kind of material of which the tray is made.

A "cube" of ice frozen in one of the compartments of the tray will have the shape illustrated in Fig. 4. Here the ice "cube" or block 16 will have a height greater than any width. The back surface 17 will be at right angles with the bottom surface 18; the front surface 19 will be non-parallel to the back surface 17 and will be flared outwardly from bottom to top; the lower portion of the front surface 19 terminates in a curved surface 20 joining with the bottom surface 18; and the end surfaces 21 and 22 will be non-parallel, both flaring outwardly from the vertical from bottom to top.

Figs. 5, 6 and 7 illustrate diagrammatically the advantages of an ice tray which will form an ice block of the shape shown in Fig. 4. In these

figures the ice tray is indicated by the reference numeral 23, just an end wall of the tray being shown. In practice the tray may be surrounded by a coil or tube 24 for the refrigerant. The tray 23 and its coil 24 are disposed for rigid non-movement within a trough 25. The trough 25 is pivoted as at 26 and unless filled with water will remain in the position illustrated.

The operation of the device is as follows. Assuming the tray is filled with water, the refrigerant passing through coil 24 will freeze the water in the tray 23. When it is desired to release the ice, warm refrigerant gases are caused to pass through the coil 24 and simultaneously the trough 25 is filled with water. The combined action of the warm refrigerant gases and of the water loosens each ice block 16 within the tray and each ice block begins to float to the surface 27 of the water. This stage of the operation is illustrated in Fig. 6.

As each ice block 16 leaves its compartment it will, because of its shape, begin to turn so that its axis will be horizontal instead of vertical. This turning movement as the ice block leaves its compartment is facilitated by the curved surface 20 of the ice block as will be apparent. Finally, the ice block 16 floats to the surface 27 of the water in the trough and assumes substantially the position illustrated in Fig. 7. The water has now substantially filled the trough and its weight has changed the center of gravity of the trough causing the trough to tilt on its pivotal axis 26, thus dumping out water and the ice blocks 16. The water supply is cut off and the trough rights itself taking again the position shown in Figs. 5, 6 and 7. Some water remains in the trough and fills the tray for the next freezing operation. Excess water is drained from the trough through the small drain hole 28 in the bottom thereof.

As hereinbefore indicated this general system of operation is described in my copending application, Serial No. 605,570. That application, however, does not disclose the particular shaped ice tray capable of making ice blocks such as 16, which upon loosening will rise and turn in the manner described herein.

Now that the invention has been disclosed, it will be apparent that changes in the form and construction of the parts may be made within the scope of the invention. For example, instead of constructing the tray of pieces of sheet metal brazed or otherwise secured together the tray could be comprised of a single molded or cast piece of metal or other material such as plastic. The important consideration, however, is that the compartments in the tray have such shape and dimensions as will produce ice blocks which, like that shown in Fig. 4, will, when released, respond in the manner illustrated and described.

I claim:

1. An ice block tray comprising at least one compartment for freezing liquid therein into ice, said compartment being constructed of sheet material and having a bottom wall, front, back, and end walls, the back and bottom walls being disposed substantially at right angles to each other and being comprised of a single piece of the ma-

trial, the front wall being disposed non-parallel to the back wall, the end walls and the front wall being comprised of another single piece of the material, the forward end of the bottom wall terminating in a curved upwardly turned flange secured to the lower portion of the front wall, the distance between opposed walls being progressively greater from the bottom to the top of the compartment, and the height of the compartment being greater than the distance between any two of the walls.

2. An ice block tray comprising at least one compartment for freezing liquid therein into ice, said compartment being constructed of sheet material and having a bottom wall, front, back, and end walls, the back and bottom walls being disposed substantially at right angles to each other and being comprised of a single piece of the material, the front wall being disposed non-parallel to the back wall, the end walls and the front wall being comprised of another single piece of the material, the forward end of the bottom wall terminating in a curved upwardly turned flange secured to the lower portion of the front wall, the end walls being non-parallel with respect to each other and being inclined outwardly from the vertical from bottom to top, the distance between the front and back walls being progressively greater from bottom to top, and the height of the compartment being greater than the distance between any two of the walls.

3. An ice block tray comprising a plurality of compartments for freezing liquid therein into ice, said compartments being constructed of sheet metal and having a bottom wall, front, back, and end walls, the back and bottom walls being disposed substantially at right angles to each other and all of the back and bottom walls being comprised of a single piece of sheet metal, the front wall of each compartment being disposed non-parallel to the back wall, the end walls and the front wall of each compartment being comprised of another single piece of sheet metal, the forward end of the bottom wall terminating in a curved upwardly turned flange which is secured to the lower portion of the front wall of each compartment, the distance between opposed walls of each compartment being progressively greater from the bottom to top thereof, and the height of each compartment being greater than the distance between any two of its walls.
